ATTORNEY.

UNITED STATES PATENT OFFICE.

CHARLES C. BLACKMORE, OF DAYTON, OHIO.

CURTAIN-SUPPORTING DEVICE FOR AUTOMOBILE DOORS AND THE LIKE.

Application filed September 18, 1919. Serial No. 324,278.

To all whom it may concern:

Be it known that I, CHARLES C. BLACKMORE, citizen of the United States, residing at Dayton, in the county of Montgomery 5 and State of Ohio, have invented certain new and useful Improvements in Curtain-Supporting Devices for Automobile Doors and the like, of which the following is a specification, reference being had therein to the 10 accompanying drawing.

This invention relates to curtain supporting devices for automobile doors and the like.

Many automobiles are now provided with 15 rods adapted to be removably mounted at the free edge of the door and to support the edge of the storm curtain on the door so that the latter will open and close with the door.

20 The object of the present invention is to provide a simple, inexpensive and efficient device for removably mounting these rods on the door.

A further object of the invention is to 25 provide such a device, which will yieldably hold the rod, and consequently the edge of the door curtain, in engagement with the adjacent portion of the fixed curtain but will permit the edge portion of the door curtain to swing outwardly.

It is also an object of the invention to 30 provide a curtain rod of such a character that the edge of the door curtain will be held in close contact with the adjacent portion of the fixed curtain.

In the accompanying drawings Fig. 1 35 is a plan view of a portion of a side wall of the automobile body, showing the curtain supporting rod mounted thereon; Fig. 40 2 is an elevation of the attaching device, showing the same secured to the door; Fig. 3 is a transverse section taken on the line 3-3 of Fig. 2; Fig. 4 is an enlarged detail view, showing the connection between the curtain rod and the 45 lower end of the attaching device; Fig. 5 is a perspective view of a portion of a curtain rod, showing a modified form of the attaching device; and Fig. 6 is a detail view, showing another slight modification of the attaching device.

In Fig. 1 of the drawings I have shown 50 a portion of the automobile body at 1, comprising the usual door 2. Mounted on this door, near the free edge thereof, is a rod 3, to which is connected the adjacent edge

of the storm curtain 4 for the door. This rod comprises a portion, or shank 5, adapted to be seated in a suitable socket carried by the door and is preferably offset from the 60 body portion of the rod and connected thereto by a transverse portion 6. By thus offsetting the body of the rod from the shank, the former is positioned beyond the free edge of the door and the curtain, which is secured thereto, will be caused to overlap the adjacent portion of the fixed curtain on the body 1. The door is provided with a suitable attaching device to secure the rod thereto and this attaching device is usually 70 in the form of a socket to receive the shank 5 of the rod, which socket may be mounted in, or on, the door near the free edge thereof. It is desirable that the connection between the rod and the door shall be yieldable, so that the rod will press the edge of the door curtain firmly against the fixed 75 curtain when the door is in its closed position. I have provided a very simple and inexpensive socket, which will firmly support 80 the rod in such a manner that it can be quickly and easily placed in position thereon or removed therefrom and will permit the same to have a slight yielding movement.

As shown in the present drawings, this socket 85 comprises a coil 7 of spring wire, or other suitable resilient material, which is tubular in shape and of such an internal diameter that the rod may be easily inserted in, or removed from, the same and is of such 90 length that the rod will be held firmly in an upright position. One end of the coil, or socket, is so connected with the rod as to be held against rotary movement relatively thereto, while the other end of the coil is 95 fixed against rotation with the rod. In the present construction, the end of the wire, of which the coil is formed, is bent transversely of the coil at the lower end thereof, as shown at 18, and the lower end of the 100 rod is provided with a notch, or recess, 9 to receive this transverse end portion of the wire. In this manner the connection between the rod and the ends of the coil is separable, but is easily established when the rod is inserted in the socket and this connection serves 105 not only to hold the parts against relative rotation, but also to limit the downward movement of the rod and thus support the same in its proper position on the door. At 110 the upper end of the coil the end of the wire projects tangentially from the coil, as shown

at 10, so that it may be secured to the supporting structure in such a manner as to hold this portion of the coil against rotation.

5 The coil, or socket, may be mounted in, or on, the door in any suitable manner. When mounted within the door, it is arranged in alinement with an opening 11 formed in the top rail thereof. In that 10 form of the device shown in Figs. 2 and 3 I have shown the socket as secured in position by means of metal bands, or clips, 12 and 13, having portions to fit about the upper and lower ends of the socket, respectively, and having end portions which may be secured to the supporting structure in any suitable manner, as by screws or rivets. These clips hold the socket firmly in its proper position without interfering with its 20 resiliency. If desired, the lower clip 13 may be provided with a lip 14 to engage the coil and hold it against downward movement. The upper clip 12 is provided with a recess 15 to receive the end 10 of the wire 25 and hold the same against movement.

The clips 12 and 13 may, if desired, be dispensed with, and the wire from which the coil is formed shaped to provide the necessary fastening means. In Fig. 5 of 30 the drawings, the upper end portion of the wire is bent to form laterally extending portions, or ears, 16 and 17, having openings to receive screws, or other attaching devices. When secured to the door in this manner, 35 the socket will be held firmly in its position and is wholly self-contained. In Fig. 6 I have shown the socket as having the upper end of its wire shaped to form a single ear 18, by means of which it may be secured 40 to the door. With this construction the clip 13 at the bottom of the coil may be retained, if desired, to hold the socket more firmly in a vertical position, although the fastening at the top will ordinarily accomplish 45 this in a satisfactory manner.

It will be apparent, in the foregoing description, that I have provided a socket of the character described, which is of a very simple and inexpensive construction, which 50 can be very quickly and easily attached to the door, and which will hold the curtain rod firmly in its proper position, but will permit it to have such yielding movement as may be necessary to enable the rod to hold 55 the edge of the door curtain in contact with the fixed curtain. Further, the axis of the curtain rod being spaced from the edge of the door the edge portion of the curtain may be swung outwardly relatively to the 60 door and to the body of the curtain to provide an opening through which the hand may be extended for signalling purposes, and as soon as the pressure on the rod is relieved it will automatically restore the curtain 65 to its closed position. As shown in

Fig. 1, the position of the rod on the door is such as to provide a relatively small opening, such as would be required for signalling with the hand, but obviously the rod may be so located as to provide an opening of 70 any desired size.

The rod is usually arranged in the inner portion of the door, so that it is spaced some little distance from the outer surface thereof and, in order that the main portion of 75 the rod, to which the curtain is attached, may bear against the fixed curtain, I prefer that the transverse, or connecting part 6 of the rod shall be curved after the manner shown in Figs. 1 and 5.

While I have shown and described one embodiment of my invention, with certain minor variations thereof, I wish it to be understood that I do not desire to be limited to the details shown, as various modifications may occur to a person skilled in the 80 art.

Having now fully described my invention, what I claim as new and desire to secure by Letters Patent is:

1. The combination with an automobile door or the like and a curtain therefor, of a curtain supporting rod attached to one edge of said curtain and having an offset portion yieldably mounted on said door at a point spaced from the edge thereof for movement about a vertical axis, whereby the edge portion of said curtain may be swung outwardly relatively to said door and to the body of said curtain.

2. The combination with an automobile door or the like and a curtain therefor, of a curtain rod comprising a shank rotatably mounted on said door at a point spaced from the edge thereof for movement about a vertical axis, a portion extending laterally from said shank, and a portion extending upwardly from said laterally extending portion and adapted to be attached to said curtain, and a spring acting on said rod to 100 yieldably hold the last mentioned portion thereof against outward movement.

3. A curtain supporting device for an automobile door or the like comprising a rod supporting device adapted to be mounted on an automobile door and capable of yielding movement about a vertical axis, and a curtain rod having a lower portion removably mounted in said device, held against rotation relatively thereto, and having an upper vertical portion offset from said lower portion and adapted to be attached to the edge of a curtain and to normally support said edge of said curtain in overlapping engagement with an adjacent curtain.

4. A curtain supporting device for an automobile door or the like comprising a resilient socket adapted to be mounted on said door and capable of yielding movement about a longitudinal axis, a curtain support-

ing rod mounted in said socket for movement about a longitudinal axis and adapted to be inserted in and removed from said socket at will, and means for connecting one 5 end of said rod with the adjacent end of said socket to hold the rod and said end of the said socket against relative rotation, the other end of said socket being held against rotation with said rod.

10 5. A curtain supporting device for an automobile door or the like comprising a spring wound to form a socket which is adapted to be mounted on an automobile door, a rod mounted in said socket 15 for movement about a longitudinal axis and adapted to be inserted in and removed from said socket at will, said rod and one end of said spring having parts arranged to be brought into cooperative relation when said 20 rod is inserted in said socket to hold said rod and said end of said spring against relative rotation, and means to hold the other end of said spring against rotation with said rod.

6. A curtain supporting device for an 25 automobile door or the like comprising a spring wound to form a socket which is adapted to be mounted on an automobile door, a rod mounted in said socket for movement about a longitudinal axis and adapted 30 to be inserted in and removed from said

socket at will and having in one end thereof a recess, said spring having a part adapted to enter said recess when said rod is inserted in said socket and to hold the rod against rotation relatively to the adjacent 35 end of said spring, and means to hold the other end of said spring against rotation with said rod.

7. A curtain supporting device for an automobile door or the like comprising a 40 spring wound to form a socket which is adapted to be mounted on said door, a rod mounted in said socket for movement about a longitudinal axis and adapted to be inserted in and removed from said socket at 45 will, said rod and the lower portion of said spring having parts arranged to be brought into cooperative relation by the insertion of said rod in said socket to hold said rod and said portion of said spring against relative 50 rotation, and the upper portion of said spring having a part shaped to provide means for securing said socket in position on a supporting structure and for holding the upper end portion thereof against rotation 55 with said rod.

In testimony whereof, I affix my signature hereto.

CHARLES C. BLACKMORE.
